CLAIM

The ornamental design for a container cap, as shown and described.

DESCRIPTION

FIG. 1 is a bottom front perspective view of the container cap of the present invention;

FIG. 2 is a bottom rear perspective view thereof;

FIG. 3 is a top front perspective view thereof;

FIG. 4 is a bottom view thereof;

FIG. 5 is a top view thereof;

FIG. 6 is a front view thereof;

FIG. 7 is a rear view thereof;

FIG. 8 is a left side view thereof;

FIG. 9 is a right side view thereof; and,

FIG. 10 is a bottom front perspective view thereof showing the new design in a non-claimed environment.

In FIGS. 3 and 5, the broken lines show portions of a container cap that form no part of the claim; in FIG. 10, the broken lines depict environment that forms no part thereof.

1 Claim, 7 Drawing Sheets
